UNITED STATES PATENT OFFICE

HERBERT M. FRIENDLY, OF CHICAGO, ILLINOIS

AUTOMATIC TELEPHONE SYSTEM

Application filed August 24, 1927. Serial No. 215,034.

The present invention relates to telephone systems; more particularly so-called automatic or machine switching telephone systems.

5 *General objects*

An object of the present invention is to enable a subscriber of the automatic telephone system who has changed his telephone number to a random location in the exchange system to be reached over the general trunking system of the exchange at his new number responsive to calling his old telephone number.

It is not new to cross-connect by jumper the terminals of the old telephone number to the terminals of the new telephone number so that calls directed to the terminals corresponding to the old number will be thereby in fact connected to the terminals of the new telephone number. However, the present invention is more particularly directed to the situation wherein the new telephone number is tributary to a remotely situated central office of the exchange system, and therefore 25 having a different office prefix. It is also directed to the situation wherein a subscriber having a single line will subscribe for a group of lines having a single calling number for the group, causing any call completed to the 30 old number to be thereupon forwarded to his new group as a whole.

The present invention thus contemplates that when a new line number is assigned to a subscriber, particularly when it is not practicable to jumper the old line terminals to the new line terminals, call forwarding apparatus will be seized through the terminals of the old line when it is called, the calling party perhaps not being beforehand apprised of the fact the wanted party has a new line number. When this apparatus is seized by the connector when its wipers are set upon the terminals of the old line, and in view of the pre-set condition of said apparatus, will 45 cause a train of impulse series to be sent and

otherwise control the concerned circuits to extend the call to the terminals of the new line, regardless of into which central office of the exchange it is tributary.

It will be understood that in place of the 50 call being forwarded to a new line of the subscriber having the line called the apparatus may cause the call to be extended to some other random telephone line of the system, or to an operator employed by the operating 55 concern, as the information operator, for example.

The present invention thus lends itself to saving calls to a subscriber who has moved to another central office district of the exchange, without the delay or annoyance to the calling party as would be occasioned if the terminals of the line called were extended directly to an information operator of the operating concern who would inform the 60 calling party of the new number after which the calling party would be obliged to hang up and initiate a new call. The call will be extended to the concerned subscriber's new line without delay, the called party on said new 65 line perhaps apprising the calling party of the number change so that future calls may be made direct to the new line by calling the new line number. A specific tone source T^2 is provided which not only apprises the called party 70 at the time he removes his receiver in responding that the call is one forwarded from his old number, but it also apprises the calling party at the time the new line is seized that the call has been forwarded and to therefore 75 be prepared for a slightly longer responding delay occasioned by the time taken in sending the impulse train in forwarding the call.

The present invention thus enables a subscriber who contemplates being absent from the city for a time arranging with the telephone operating concern to have all the calls directed to his line forwarded to some predetermined random line of the exchange. The 80 85 90 95

latter may be a trunk line leading to the desk of an operator in the employ of the operating concern, or it may be the line of some random subscriber of the system who has consented 5 to respond to the calls for the absent subscriber.

A feature of the present invention is that the call meter of the line primarily called by the calling party will register a specific for- 10 warding toll against the subscriber primarily called. This toll is in addition to and separate from the toll assessed against the calling telephone for the call to the terminals of the line primarily called. Of course, any desired plan 15 of metering or assessing toll charges may be employed since the call from the telephone initiating the call to the line primarily called is essentially a normal call to that line, while the forwarded portion of the call is essential- 20 ly a normal call from the primarily called line.

The same line switch B and call meter of the primarily called subscriber's line is used as was formerly used when the call was in- 25 initiated on its corresponding line from telephone A, which telephone A is now disconnected.

In carrying out the present invention, the operating concern will provide a sufficient 30 number of units of equipment apparatus shown in Figs. 2 and 5. It will then introduce these units into the desired lines as required, perhaps contingent upon specific rental pay- 35 ment. To introduce the said equipment units, connections between certain line terminals are opened, and certain line terminals are jump- 40 ered to the unit involving Figs. 2 and 5 em- ployed. The designated jumpers in Fig. 5 are then run in accordance with what line is 45 to receive the forwarded calls. In the ex- ampled embodiment illustrating the present invention the call primarily completed by connector E in Fig. 4 to line No. 22311 is forwarded through the line switch B, indi- 50 vidual to the latter said line, to line No. 33241. Of course, any other suitable kind of line switch may be employed; in fact a so-called 55 finder switch mechanism may be employed in place of the line switch B. Using the same line switch B as formerly used by the sub- 60 scriber insures the same class of rating to the forwarded calls as existed for originated calls of the subscriber with the least equipment change and record clerical work.

There are additional operative features of 65 the present invention which will be described in the descriptions to follow relating to the exemplary embodiment of the present invention chosen to explain it, having in mind that other features not specifically mentioned will be apparent from the descriptions and drawings. The invention is capable of varied modification without departing from its scope 70 as defined by the subjoined claims.

Drawings

With reference to the accompanying draw- 75 ings:-

Fig. 1 shows a disconnected telephone A 70 and individual primary line switch B, the latter said switch in common with other line switches (not shown) having access to the group of secondary line switches containing the secondary line switch C.

Fig. 2 shows apparatus specific to the pres- 75 ent invention introduced between the connector bank terminals and the leading-in terminals of line switch B of the line primarily called.

Fig. 3 shows a well known selector F ac- 80 cessible from the switch group containing the secondary line switch C, together with other indicated automatic switches and calling and called telephone lines.

Fig. 4 shows a well known connector E 85 having access to the terminals of subscribers' lines.

Fig. 5 shows the impulse train transmitting apparatus cooperative with the apparatus shown in Fig. 2.

The various figures of the drawings are as- 90 sembled so that the designated lines extending towards the margins of the sheets containing them register.

95

Equipment

The telephones A, A', AA and A³ are of the well known common-battery series automatic type.

The primary line switch B and the second- 100 ary line switch C are of the well known rotary type as described in the third edition of Hershey's Automatic Telephone Practice, page 53. The line switches LS and LS' are 105 like the line switch B.

The first selector F is of the well known type, sometimes designated as the Powell selector, and described on pages 59 to 61 in said book. The selectors G, H, J, K, L, N, P and Q indicated in Fig. 3 are like selector F.

The connector E shown in Fig. 4 is of the well known type as shown in Fig. 73 of the fourth edition of the said Hershey book.

The switch NO⁵ in Fig. 5 is generally like switch LS in mechanical construction, but is arranged to have a home position to which it returns and at which it rests when not in use in a call. The drawing Fig. 5 shows this switch NO⁵ in the home position.

The switch DF⁶ is mechanically like switch NO⁵. However, the wiper 524 of switch DF⁶ is so designed as to not disen- 115 gage a bank terminal it is resting upon at any time until it contacts with the next succeed- 120 ing bank terminal in order that when it once receives ground from source 528 it will continue to receive it until it advances to the home position as shown in the drawing.

Of course, the specific switches may be sub- 130

stituted for by any switch meeting the requirements, without departing from the spirit of the present invention. The present invention primarily resides in Figs. 2 and 5, co-operated with elements of a well known automatic telephone system illustrated in Figs. 1, 3 and 4.

Call from telephone A³ to telephone line 22311 under the condition that the subscriber of the called line has a new line 33241 tributary to a different central office than formerly

In view of the well known operation of the line switch LS, first selector J, second selector N, third selector Q and connector E, and in view of the references to the third and fourth editions of the said Hershey book, it is thought unnecessary to recite the detailed operations of the switches responsive to the directive operations of the calling party at telephone A³ for causing the wipers 424 to 426 of the connector E to be set upon the bank terminals 427 to 429, respectively, of the line Number 22311.

Let it be assumed that the bank terminal 427 constitutes battery potential derived through the winding of relay 203 over an obvious circuit path, due to no other connector of the group containing connector E being in seizure with the multiples of said terminals 427 to 429 at the time said terminals are selected by connector E. The wiper closing relay 431 in connector E will actuate and lock to effect the seizure of the latter said terminals, changing the battery potential previously existing on bank terminal 424 to ground potential to guard the seized line switch B against further seizure by another connector of the group containing connector E, should some other party call for the line Number 22311.

Ground applied to bank terminal 427 is continued over conductor 432, armature 202 to the winding of relay 203, the latter said relay actuating. A circuit path can now be traced from the winding of slow-releasing line relay 19 in the primary line switch B, armature 20, conductor 21 make-before-break spring 206, armature 207, conductor 208, armatures 501 and 502 in multiple, conductor 503, armature 209, make-before-break spring 212, conductor 213, armature 24 to ground on the resting contact thereof. It will be noted that the traced loop including the armatures 20 and 24 of the primary line switch B is equivalent to the condition of closing a conductive circuit path through the telephone A, assuming the conductors 21 and 213 disconnected by opening the jumpers to terminals 25 and 27 and the terminals 25—26 and 27—28 connected by tie conductors, respectively. The terminals 25, 27 and 29 were formerly connected by suitable tie conductors to terminals 214, 215 and 216, respectively. The switch B will thus operate in the well

known manner to extend the connection from the multiplied armatures 501 and 502 to a secondary line switch as C and the latter said switch will then further extend the connection to a first selector as F.

It will be noted, in this connection, that the conductor 213 is maintained at ground potential first by the ground applied through the resting contact of armature 24 and then by the ground applied through the resting contact of armature 30. At least no battery potential will exist on conductor 213 until the selector F has been seized, so that in place of dead ground applied from the resting contact of armature 24 or 30, the resistance of the lower winding of relay 301 to ground is applied over conductors 302 and 31 to conductor 213. Under the latter condition battery applied through the upper winding of relay 301 leads over an obvious path to ground through the lower winding of the latter said relay. This will provide sufficient battery potential on conductor 213, applied through armature 214, to operatively energize the upper winding of relay 217, which relay will lock through armature 218 to conductor 432 as long as conductor 432 remains grounded.

Ground is now applied through armatures 221 and 222, conductor 223 to the winding of relay 504, the latter said relay actuating to start the predetermined directive impulse series train corresponding to Number 33241 of telephone A', as will appear presently.

Bank terminals 505 to 509 cooperative with wiper 513 correspond to the first to the fifth digit, respectively, of any train of five digit series to be sent in forwarding the call from the line corresponding to telephone A, for example. Inasmuch as in the assumed case the call is to be forwarded to telephone Number 33241, the terminals on the cross-connecting rack designated X in Fig. 5 corresponding to said bank terminals 505 to 506 will be jumpered to terminals Y on the cross-connecting rack having numerical digit value corresponding with the numerical order rank of the digits of the latter said telephone number, the terminals Y being designated in accordance with their numerical digit value to correspond to the bank positions of the switch DF⁵.

It will be clear, presently, that if it were desired to forward the call to any other telephone number, it would only be necessary to correspondingly run the five jumpers leading from the numerical order terminals X corresponding to 505 to 509 to the corresponding digit terminals Y.

Relay 504 being actuated, armature 511 applies ground over conductor 512 through wiper 513, bank terminal 505 to the digit terminal in the group Y corresponding to digit 3. Armature 517 applies ground received through wiper 513, bank terminal 505,

wipers 539—536 to the winding of relay 515, the latter said relay actuating and locking to grounded armature 514, it being noted that relay 515 can only actuate provided the 5 wipers on shaft 533 are in their drawn positions.

Sending of forwarding impulses

The ground interrupter I^5 revolves at approximately twelve revolutions per second, being the rate it is desired to send directive open impulses to the switches forwarding the call. The first open impulse delivered to conductor 516 after the actuation of relay 515 10 will be applied through armatures 518 and 519 to operate motor magnet 520 and relay 521 in multiple, respectively. The motor magnet 520 and the relay 521 will successively attract their armature so long as armatures 15 518 and 519 remain retracted. The wiper 524 is stepped to bank terminal 527 responsive to the operation of the interrupter I^5 so that ground 528 is then applied over conductor 20 529, armature 530 to the winding of relay 531, the latter said relay actuating.

Sending first digit impulses in forwarding call

The wipers on shaft 533 will be driven forward responsive to the operation of interrupter I^5 until the terminal 535 corresponding to digit 3 is encountered by wiper 536, the relay 531 being maintained constantly actuated from the ground 528, and the relay 25 521 transmitting successive open impulses effective to the selector F.

At the time wiper 536 engages bank terminal 535 three open impulses from armature 501 on relay 521 will have caused the wipers 40 of the selector F to align with the third level of bank terminals. Also, at the time wiper 536 engages bank terminal 535 a circuit path can be traced from grounded armature 511, wiper 513, bank terminal 505, jumper 538, 45 digit terminal 3 on the cross-connecting rack group Y, bank terminal 535, wiper 536, wiper 539, bank terminal 540, conductor 541 to the winding of slow-releasing relay 523, the latter said relay actuating, armature 530 locking it through wiper 524 to ground 528 so 50 long as wiper 524 is off the bank terminal it is shown resting upon.

When the relay 523 actuates, armatures 501 and 502 will retract to maintain the closure 55 of the circuit path including the conductors 208 and 503, in order to give selector F time to rotate-in and seize the first idle trunk leading to selector G in the direction of the telephone A'. Armature 545 applies ground 60 received from conductor 529 over conductor 546 and through interrupter contact and armature 547 to operate the motor magnet 520 to restore the wipers on shaft 533 to the drawn position, at which position the ground 65 53 is removed from conductor 529.

Sending second digit impulses in forwarding call

Armature 549 applies ground to the winding of motor magnet 550, so when relay 523 70 deactuates the wipers on shaft 552 will be advanced one step. Wiper 513 now applies ground to bank terminal 506 and over jumper 553 to bank terminal 535, corresponding to digit 3, as before. Also, due to the deactuation of relay 523 the interrupter I^5 will start 75 driving the wipers on the shaft 533 in the manner before described until the wiper 536 encounters grounded bank terminal 535, causing three open impulses to be transmitted from armature 501 effective to selector G, the wipers on shaft 533 restoring to the drawn position thereafter as before described when the first series of three open impulses were sent to selector F. The shaft 552 will be caused 80 to advance upon its wipers one step when relay 523 deactuates following the sending of the second digit 3. Wiper 513 now applies ground to bank terminal 507 and over jumper 556 to bank terminal 557 corresponding to 85 digit 2.

Sending third digit impulses in forwarding call

The wipers on shaft 533 will now be driven 90 until wiper 536 encounters bank terminal 557, at which time the relay 523 will actuate and lock and the wipers on shaft 533 will be restored to the drawn position in the manner as before described, the armature 501 having sent a series of two open impulses effective to the selector H.

Sending fourth and fifth (last) digit impulses in forwarding call

In view of foregoing descriptions and the 100 jumpers 561 and 562, it will be clear that two more series of open impulses will be sent. The series corresponding to jumper 561 will be a series of four impulses, and the series corresponding to jumper 562 will be a single 105 impulse. The last two series serve to set the connector R on the terminals of the line Number 33241 (assumed idle), leading to telephone A'. The connector R will thereupon 110 send ringing current to operate the signal bell at telephone A'.

Excluding impulse sending apparatus

At the time the motor magnet 550 retracts 120 its armature 571 the fifth time, following the termination of the fifth digit series, ground is applied from armature 514, lower inside armature of relay 515, bank terminal 563 (where ground potential has existed since the relay 515 first actuated and so constantly maintained), wiper 564, conductor 565, make-before-break spring 230 to the winding of relay 232, the latter said relay actuating and locking through armature 202, conductor 432, 125 130

bank terminal 427, wiper 424 to ground on make contact of attracted armature 433.

Responsive to the actuation of relay 232, the relays 203 and 504 will deactivate in sequence. Under the present condition the extension to the telephone A' from bank terminals 428-429 has the windings of the polarized relay 233 bridged across the talking conductors 21-213 with the armature of said relay 233 tilted counter-clockwise into the dotted position designated "Ring. pos.", the armatures 235-236 being attracted.

Slow-releasing relay 237 is energized so that tone from source T² is applied through armature 240, audible to the party at telephone A³, indicative that the call has been forwarded, the periodic induction tone from the ringing generator G⁴ being also heard, the latter indicative that the connector E has seized, it having been applied from the time the connector relay 431 actuated.

Responding at telephone A'

When the receiver is removed from the switch-hook of telephone A', the current projected back from the front-bridge relay in the connector R responsive to the actuation of the back-bridge relay therein will be reversed in direction through the windings of the polarized relay 233, under which condition the armature of relay 233 will tilt clock-wise into the dotted position designated "Ans. pos.", so that the relay 241 will be operatively energized, the relay 237 deactivating consistent with its slow-releasing characteristic, but the latter said relay sustaining long enough for the party responding at telephone A' to perceive the tone from source T² to apprise him that the call was forwarded from the terminals of a line primarily called. This latter information prompts the responding party to inform the calling party of his new telephone number, so that calls to telephone A' may thereafter be made direct. The latter affords shorter path as well as obviating the forwarding charge as would be registered on the call meter associated with the line switch B, at the time the party at telephone A' responds. The said call meter has two windings. The lower winding is an electro-polarizing winding sufficiently strong to sustain its armatures after they attract so long as there is ground on the release trunk conductor 16. The upper winding energized cumulatively with the lower winding when the current is reversed through it when the called party at telephone A' removes his receiver. The armature 41 short-circuits the upper winding and the resistor 42. Meters operating thus are not new in the art as applied to simple calling lines.

Also, responsive to the removal of the receiver of the called telephone A', the relay 241 will cause its armature 243 to connect the retardation coil 245 in bridge between the

bank terminals 428-429 to energize the ring-cut-off relay 438 in connector E, followed by the actuation of the back-bridge relay 442. So that the current will not only be reversed back to the polarized relay 233 responsive to the subscriber at telephone A' removing the receiver from the switch-hook, but the current will be reversed back over the line including the calling telephone A³ by the operation of the relay 442, consequent thereto. The latter reversal will cause the call meter of telephone A³ to register a call. A call is thus registered against each telephone A³ and A for the completed call which was forwarded to telephone A'.

Talking path between calling telephone A³ and called telephone A'

When the relay 241 actuated, attracting armature 243, the talking path from telephone A³ to conductors 439-440 is continued through condensers 251-252, springs 206-212, conductors 21-213, armatures 20-24, respectively, and over the heavy talking conductors, including conductors 31 and 302 to telephone A'.

Subscriber at telephone A' replaces receiver on switch-hook while subscriber at telephone A³ retains his receiver off

If the subscriber at telephone A' first replaces his receiver after terminating the conversation the deactivation of back-bridge relay in connector R resultant thereto will cause the direction of current to be restored so as to operate the polarized relay 233 to deenergize relay 241 and operatively energize relay 237 to apply tone source T² and also remove the retardation coil 245 from the bridge, so that the back-bridge relay 442 in connector E will deactivate. The winding of polarized relay 233 is still in series with the front-bridge relay in connector R, so the latter said connector is still in seizure of the line leading to telephone A'.

Subscriber at telephone A³ replaces receiver on switch-hook

Upon the subscriber at telephone A³ now replacing his receiver on the switch-hook, the front-bridge relay and its local slow-releasing relay 446 in connector E will deactivate and cause the obvious circuit for the release magnet of connector E to operate to restore said connector E. This will remove the ground from conductor 432, so that the relay 232 will deactivate, thus removing the winding of polarized relay 233 from the said series relation with the front-bridge relay in connector R, so that the said connector R and antecedent switches H, G, F, C and B employed in forwarding the call will be thereupon restored. The switches Q, N, J and LS antecedent to connector E and dependent upon relay 446 will also restore so that the

circuits employed in the connection are now normal and in readiness for new use.

Subscriber at telephone A³ replaces receiver on switch-hook while subscriber at telephone A' retains his receiver off

If the subscriber at telephone A³ first replaces his receiver after terminating the conversation, the deactuation of the front-bridge relay 446 in connector E resultant thereto will cause a circuit to be prepared for the release magnet of said connector E and the ground removed from the release trunk so that the antecedent switches Q, N, J and LS will restore, the said connector E remaining in seizure, since the retardation coil 245 is still in series with the back-bridge relay 442. The winding of the polarized relay 233 is still in series with the front-bridge relay of connector R, so that the replacing of the receiver at telephone A³ produces no operative effect beyond connector E.

Subscriber at telephone A' replaces receiver on switch-hook

Upon the subscriber at telephone A' now replacing his receiver on the switch-hook, the back-bridge relay of connector R will deactuate to restore the direction of current traversing the winding of polarized relay 233, so that the relay 241 will be deenergized and thereby remove the retardation coil 245 from the bridge, so that the back-bridge relay 242 in connector E will deactuate. The winding of the polarized relay 233 is still in series with the front-bridge relay in connector R, so that the latter said connector is still in seizure of the line to telephone A'.

When the back-bridge relay 442 in connector E deactuates, it closes the obvious circuit for the release magnet of connector E to operate to restore said connector E. This will remove the ground from conductor 432 so that relay 232 will deactuate, thus removing the winding of polarized relay 233 from the said bridge relation with the front bridge relay in the connector R, so that the said connector R and antecedent switches H, G, F, C and B employed in forwarding the call will thereupon be restored, the circuits employed in the connection being now normal.

Restoration of impulse sending apparatus

At the time relay 203 deactuated, following the last impulse of the train, the armature 222 opened the energizing circuit for relay 504 and its dependent relay 515. Ground from armature 569 will be applied through the interrupter armature on motor magnet 550, causing the shaft 552 to restore the wipers thereon to the drawn position. Ground from armature 571 will be applied through wiper 572 and through the interrupter armature 547, causing the shaft 533

to restore the wipers thereon by driving them forwardly to complete a cycle to the home position shown in the drawing.

Call forwarding apparatus in Fig. 5 cannot be seized if the wipers on shafts of element's NO⁵ and DF⁵ are not in the drawn position

It will be noted that if the call is abandoned by the calling party at telephone A³ before the impulse sending mechanism has completed its operation and relay 232 has actuated and locked, the busy ground will be removed from bank terminal 427 and multiples thereof. The said terminals are thereupon subject to seizure, although the wipers of the elements NO⁵ and DF⁵ may not have restored to the drawn position. In order to prevent the call made under this condition being vitiated, the relay 515 is disabled from actuating until the wipers of the elements NO⁵ and DF⁵ have restored to the drawn position, so that even if the terminals corresponding to terminals 427 to 429 are seized while the said wipers are not in the drawn position, the said wipers will restore before the armatures 569 and 571 can attract and before the upper armature of relay 515 can attract to apply ground impulses to the motor magnet 520. Unless the wipers of the elements NO⁵ and DF⁵ are in the drawn position there can be no ground from armature 511 applied through the armature 517 to initially energize the winding of relay 515 so that impulses can be applied to the winding of relay 521 to cause forwarding impulses to be effectuated.

Line leading to telephone A' encountered busy when call is forwarded thereto

If the line leading to telephone A' is encountered busy when the call primarily directed to telephone A (line Number 2211) is forwarded thereto, the busy tone applied to the upper talking conductor in connector R will pass over the upper talking conductor of the connection to conductor 21, spring 206, armature 235, condenser 251, conductor 439, bank terminal 428, tone condenser 445, audible to the subscriber at telephone A³, having in mind that this tone will be particularly distinguishable during the silent ringing periods from generator G⁴, since there will be a generator tone during the live ringing periods.

Calls to a plurality of lines may be forwarded by the same impulse train transmitting apparatus to a specific line

The terminals 427 to 429 correspond to the line Number 22311. The terminals 461 to 463 correspond to another random line which is connected by the indicated and designated jumpers in Fig. 2 so that the terminals 427 to 429 are in multiple with terminals 461 to 463, 130

respectively. That is to say, the telephone A' 5 may answer calls primarily directed to any one of a plurality of lines. Of course, if any one of the said plurality of lines is busy, all the rest of the lines of said plurality will be guarded against seizure. However, this method of connecting saves apparatus sets as shown in Figs. 2 and 5, connected individual to each line where the calls (which may be infrequent) are to be forwarded to the same 10 telephone number. The lines commonly served by the same apparatus set shown in Figs. 2 and 5 need not necessarily be accessible from the same group of connectors as 15 contains connector E. The lines; any plurality of them, may be served by random connector groups of the central office.

It will be clear that when the subscriber 20 having the new telephone number as 33241, fails to note the tone from source T² when responding to calls, he will know that parties calling him know his new telephone number, so that he can dispense with the facility for 25 forwarding from his old number. The operating concern can then employ the forwarding apparatus disclosed in Figs. 2 and 5 in connection with some other subscriber's line by cross-connecting it into the desired said line and also suitably changing the jumpers 30 indicated at the terminal groups X and Y in accordance with the new line to which calls are to be forwarded.

In foregoing descriptions, the call to line 35 Number 22311 was forwarded to line Number 33241, employing the primary line switch B formerly used by the telephone A when it was in service. It will be understood that the conductors 21 and 213 may be extended to a 40 primary line switch other than B, or that the unit constituting Figs. 2 and 5 may also include as a component part thereof a primary line switch having access to the secondary line switch group containing switch C. In fact, the conductors 21 and 213 may be extended to a first selector by any well known 45 or suitable means in carrying out the present invention.

Where the unit or set involving Figs. 2 and 5 also includes a primary line switch for forwarding the call to the first selector, it will then only be necessary to run jumpers indicated and designated in Fig. 2 to introduce the call forwarding apparatus with respect to a desired line. Account of the calls forwarded may be taken from the call meter of the line switch belonging to the primary line switch of the forwarding set. Of course, in place of the primary line switch, a finder switch arrangement may be employed. In 55 view of the last foregoing, it will be clear that the conductors 21-213 may correspond to the designated "line" conductors leading to the upper and lower inside armatures of relay L in Fig. 22 in the third edition of Hershey's Automatic Telephone Practice, and

under that condition calls to the terminals of line Number 22311 accessible from connector E will be forwarded through the indicated first selector to the subscriber's new line or other predetermined line.

In foregoing descriptions of the exemplary form of the present invention as applied to forwarding calls where telephone service has been discontinued on a subscriber's line has been explained. The present invention, 75 however, has other applications and uses, among which is its employment in connection with so-called private automatic exchanges. Its use in the latter connection will be where there are one or more subscribers or other 80 lines of the general exchange system that are called frequently. Apparatus corresponding to Figs. 2 and 5 is introduced between a random bank terminal set of a "local" connector corresponding to E and a line switch corresponding to B having access to main exchange trunks which terminate in an incoming 85 switch corresponding to F. Thus, when the particular main exchange line is wanted the private automatic exchange subscriber will cause the "local" connector to seize the terminals corresponding whereupon the impulse sending apparatus will send the train of impulse series to forward the call, the impulses starting when the said incoming switch is 90 ready to receive directive impulses, in the manner as has been explained with reference to selector F wherein relay 217 is caused to 95 operate to start the sending of the impulses in accordance with the jumper connections 100 between terminals X and Y of the cross-connecting rack. Thus, while the main exchange may be a system requiring five digits to be sent to reach the desired line, and the usual digit "0" may be first required to select the main exchange trunk in general main exchange calls from the private automatic exchange, the specifically arranged numbers 105 may be called by simply removing the receiver and sending two series to set the "local" connector as if a local line of the private 110 automatic exchange were wanted.

While the present disclosure illustrates switches having movable connective terminals, it will be understood that this is merely by way of illustration, and that therefore any switch mechanism having equivalent objects may be substituted without departing from the spirit of the invention, and the intent of the claims defining the exemplified disclosure.

The scope of the present invention will be comprehended in view of the broadest interpretation of the subjoined claims.

I claim:

1. In an automatic telephone system, a 125 calling line, a called line, a numerical position designation of the called line in the system with respect to the calling line, a plurality of numerical switches each said switch used as a link in effecting a connec- 130

tion by said switches from the calling line to the called line, means for directly operating certain of said switches over the calling line responsive to sending an abbreviated numerical position designation of said called line over the calling line, and automatic directive means introduced responsive to completing the said certain switch operation resultant to sending said abbreviated designation over the calling line for causing other of said switches to complete a connection from the calling line to the called line wherein all said numerical switches are links of the connection.

2. In an automatic telephone system, a switch, a movable connective terminal of the switch, a fixed terminal of the switch cooperative with the movable terminal, a called line, automatic switch mechanism for extending connection from the fixed terminal to the called line, an impulse sending device, and means responsive to selecting the fixed terminal by the movable terminal for causing the impulse sending device to generate impulses effective to automatically directly operate the switch mechanism from a point intermediate of the fixed terminal and the called line to extend connection from the fixed terminal to the called line.

3. In an automatic telephone system, a calling line, a called line, a plurality of automatic switches, impulse generating means for directly operating the respective switches to link a call extension by said switches from the calling line to the called line, said means involving a device on the calling line for generating impulses for directly operating a first portion of said switches and also involving another device on the call extension from the calling line for generating impulses for directly operating the remainder of said switches responsive to the operation of said first portion of said switches, wherein all said operated switches are talk-links of the completed call extension from the calling line to the called line, and terminals arranged for variably cross-connecting connections to cause the said another device to generate corresponding impulses at will in accordance with which called line is concerned.

4. In an automatic telephone exchange system, an automatic switch, a movable connective terminal of the switch, fixed terminals of the switch cooperative with the movable terminal, a plurality of lines, each said line having a numerical position in the exchange system, automatic numerical switch mechanism for extending connections from a random said fixed terminal to a corresponding one of said lines, and automatic means operated responsive to selecting a random said fixed terminal by the movable terminal for thereby causing said switch mechanism to operate in accordance with predetermined

numerical selective movement to extend a connection from the fixed terminal selected to the corresponding one of said lines.

5. In a telephone exchange system, a switch, a movable connective terminal of the switch, fixed terminals of the switch cooperative with the movable terminal, a plurality of numerically positioned lines of the exchange system, a plurality of automatic switches, means for causing certain of said switches to operate responsive to numerical directive control to extend a connection from a random one of said fixed terminals to a corresponding one of said lines, and automatic means operated responsive to selecting a random one of said fixed terminals by the movable terminal for causing certain of said switches to be interlinked by numerical directive control to extend a connection from the selected said fixed terminal to its corresponding one of said lines wherein all said switches are links of the completed extension.

6. In an automatic telephone exchange system, a switch, a movable connective terminal of the switch, fixed terminals of the switch cooperative with the movable terminal, subscribers' lines positioned numerically in the exchange system, a plurality of automatic switches, numerically directive control means for causing a plurality of said switches to operate to complete a connection from a random one of said fixed terminals to one of said lines, and automatic means operated responsive to selecting a predetermined one of said fixed terminals by the movable terminal for causing said switches to complete a connection from the fixed terminal selected to a particular one of said lines.

7. In an automatic telephone system, a calling line, a called line, a directive calling device on the calling line, a plurality of automatic switches for linking a connection from the calling line to the called line, means for directly operating a portion of said switches directly responsive to impulses sent from said calling device, and automatic means responsive to the operation of said switches for directly sending impulses generated at a point in the said linked call extension for operating the remainder of said switches to complete a call extension from the calling line to the called line wherein all said switches are links of the completed extension.

8. In an automatic telephone system, an automatic connector switch adapted to connect to fixed terminals of a called subscriber's line and apply current to the connection from the connector to the subscriber's line called for operating a calling signal thereon, movable terminals of the switch, fixed terminals of the switch, means for automatically operating the switch to set the movable terminals on the fixed terminals, an im-

pulse sending device, and means made effective responsive to setting said movable terminals on the fixed terminals for causing the impulse sending device to send impulses 5 from a point succeeding the connector.

9. In an automatic telephone system, an automatic linking switch through which calls are extended as a talking path, movable terminals of the switch, fixed terminals of the 10 switch, means for automatically operating the switch to set the movable terminals on the fixed terminals, an impulse sending device, another automatic switch, and means made effective responsive to setting said movable terminals on the fixed terminals for causing the impulse sending device to send a predetermined series of impulses to operate the said another switch in a corresponding manner. 15

20 10. In an automatic telephone system, a calling line, a called line, a plurality of automatic connective switches, impulse generating means for directly operating the respective switches to link a call extension by said switches into tandem links of the extension from the calling line to the called line, said means involving a device on the calling line for generating impulses for directly operating a first portion of said switches and 25 also involving another device on the call extension from the calling line for generating impulses for directly operating the remainder of said switches responsive to the operation of said first portion of said 30 switches. 35

11. In an automatic telephone system, a calling line, a called line, trunk links, an automatic connective switch terminating the respective trunk links, impulse generating 40 means for directly operating the respective switches over its corresponding trunk link to link a call extension by said links in tandem from the calling line to the called line, said means involving a device on the 45 calling line for generating impulses for directly operating a first portion of said switches and also involving another device in one of said trunk links for generating impulses for directly operating the remainder of said switches responsive to the 50 operation of said first portion of said switches.

12. In an automatic telephone system, a calling line, a called line, a plurality of automatic connective switches, impulse generating means for directly operating the respective switches to link a call extension by said switches in tandem from the calling line to the called line, said means involving a device on the calling line for generating impulses for directly operating a first portion of said switches and also involving another device on the call extension from the calling line for generating impulses for directly operating the remainder of said 65 70 75 80 85 90 95 100 105 110 115 120 125 130 switches.

switches responsive to the operation of said first portion of said switches, wherein all said operated switches are talking links of the completed call extension from the calling line to the called line. 70

13. In an automatic telephone system, a calling line, called lines, automatic switch mechanism, means on the calling line for generating automatic directive control impulses for operating the switch mechanism to effect a connection from the calling line to a desired one of said called lines, other switch mechanism, another called line, and means depending upon which of said first mentioned called lines is connected to by first said mechanism for causing automatic directive control impulses to be generated on the line called to operate said other switch mechanism to further extend the connection from the calling line to said another called line. 85

14. In an automatic telephone system, a calling line, called lines, automatic switch mechanism, means on the calling line for generating automatic directive control impulses for operating the switch mechanism to effect a connection from the calling line to a desired one of said called lines, other switch mechanism, another called line, means depending upon which of said first mentioned called lines is connected to by first said mechanism for causing automatic directive control impulses to be generated on the line called to operate said other switch mechanism to further extend the connection from the calling line to said another called line, and means 95 antecedent to said another called line for permanently indicating that a response has occurred on said another called line, regardless of the fact that the connection may be thereafter destroyed. 100 105

15. In an automatic telephone system, a calling line, called lines, automatic switch mechanism, means on the calling line for generating automatic directive control impulses for operating the switch mechanism to effect a connection from the calling line to a desired one of said called lines, other switch mechanism, another called line, means depending upon which of said first mentioned called lines is connected to by first said mechanism for causing automatic directive control impulses to be generated on the line called to operate said other switch mechanism to further extend the connection from the calling line to said another called line, a tone source, and means for applying said tone source audible on the calling line indicative that the call has been further extended from the line originally called. 110 115

16. In an automatic telephone system, a calling line, called lines, automatic switch mechanism, means on the calling line for generating automatic directive control impulses for operating the switch mechanism to effect a connection from the calling line to a de- 120 125 130

sired one of said called lines, other switch mechanism, another called line, means depending upon which of said first mentioned called lines is connected to by first said mechanism for causing automatic directive control impulses to be generated on the line called to operate said other switch mechanism to further extend the connection from the calling line to said another called line, a tone source, and means for applying said tone source audible on the said another called line indicative that the said another called line was not the line primarily called.

17. In an automatic telephone system, a calling line, a called line, automatic switch mechanism, an impulse storing and sending device on the calling line, the said impulse device for storing and thereafter sending a train of series of directive impulses to operate said switch mechanism to link a connection from the calling line to the called line, and means controlled from the switch mechanism over the called line to start the directive impulses from the sending device only when the switch mechanism is ready to receive the first impulse to start the extension of the call, and means whereby all successive impulse series of the train are sent solely self-controlled by the storing and sending device.

18. In an automatic telephone system, a calling line, a called line, automatic switch mechanism for linking a connection from the calling line to the terminals of the called line, and means individual to the called line but involved in said switch mechanism and located antecedent to the terminals of the called line for permanently indicating that a response has occurred on the called line, regardless of the fact that the connection may be thereafter destroyed.

19. In an automatic telephone system, the method of extending a call to a subscriber's new telephone line number which line number has a specific numerical position in the telephone exchange system, which method consists in generating impulses on the calling line corresponding to the numerical position and designation of the subscriber's old telephone line number and introducing impulse generating apparatus on the said old line pre-set to cause impulses to be generated thereby in accordance with the new line number so that a call directed to the said old line number will be forwarded to the said new line by automatic switch mechanism directed by said impulses generated on the old line in accordance with said pre-set impulse generating apparatus wherein the party making the call from the calling line is unaware of the new line number to which he directed the completed call solely by the impulses generated on the calling line and which impulses responded to the old line number.

20. In an automatic telephone system, the method of extending a talking connection

from a calling line to a desired numerically positioned called line of the system, consisting of directly operating numerical connective switch mechanism by directive impulse control applied over the calling line in accordance with only an abbreviated designation of said called line, to extend the connection towards but not to be called line, wherein other automatic numerical switches responsive to the operation of said switch mechanism are thereby caused to automatically operate in accordance with the remainder of the numerical designation of said called line, to complete the said extended connection to the called line, and wherein the said switch mechanism operated by directive impulses applied over the calling line forms only part of the completed talking connection from the calling line, and which said completed talking connection includes said other numerical switches.

21. In an automatic telephone system, a selective switch, a leading-in conductor for the switch, means for grounding said conductor, a relay the energizing winding of which is connected to the said conductor and short-circuited by said grounding, means for causing the switch to selectively operate, and means for causing the relay to operate from said winding responsive to completing the selective operation, the last said means involving the removal of said grounding.

22. In a telephone system, a leading-in conductor, a selective switch terminating the leading-in conductor, a directive switch accessible from the selective switch for extending connection ahead from the leading-in conductor, means for grounding said conductor, an impulse sending mechanism companion to the said conductor, a relay the energizing winding of which is connected to said conductor and short-circuited by said grounding for starting the operation of the impulse sending device to send impulses effective to the directive switch to selectively extend connection ahead from the leading-in conductor, and means for causing the relay to operate to start the sending operation responsive to completing the connection to the directive switch, the last said means involving the removal of the said grounding, whereby the directive switch is caused to be selectively operated to further extend the leading-in conductor.

23. In a telephone system, a two-section talking link consisting of near and remote sections, means for effecting connection to the near section and away from the trunk via the far section, a relay connected in bridge of the talking conductors of the far section of said link, an open pair of contacts of the near section, current for application over the far section, and means whereby depending upon the direction said current flows over the far section will determine whether or not

the said open contacts will be closed so that a series conductive path will thereby exist over the talking conductors of the near section only under the condition of the current flow over the far section being in predetermined direction.

24. In a telephone system, a talking link, means for effecting connection to the link, automatic selective switch mechanism for extending connection away from the link, an impulse sending device, and means operated responsive to effecting connection to the link for causing the impulse sending device to operate in predetermined manner to send a train of series of impulses to direct the operation of the automatic switch mechanism in corresponding manner in selectively extending connection away from the link whereby a talking connection may thereafter exist between two points via the link employed in temporary connection.

25. In a telephone system, a link circuit, an impulse sending mechanism companion to said circuit, a called line, switch mechanism for extending connection to said link circuit, automatic switch mechanism for extending connection away from said link circuit to said called line, means responsive to extending connection to the link circuit for causing the impulse sending mechanism to progressively operate in sending impulses to direct the operation of the switch mechanism, means whereby destroying the connection to the link circuit will thereby cause the impulse sending mechanism to restore from its progressed state of operation over a time interval, and means whereby the impulse sending mechanism will be disabled from again sending an impulse after its restoration is initiated until after it has become completely restored from its operated state, regardless of the fact that a new connection has been extended to the link circuit before said progressed operated state has been restored.

26. In a telephone system, a calling line, a plurality of selective switches, each said switch operated responsive to one or more impulses constituting a series applied thereto, the number of said impulses in each series determining the extent of selective operation of the switch operated thereby, an impulse series sending device on the calling line for sending a train of series, means whereby respective series of impulses sent from the calling device will thereupon operate successive said switches to form a tandem operated switch train extension from the calling line, and means operated depending upon what train of series is sent from said sending device for sending a plurality of additional series from a point on the extension from the calling line to further link in tandem a plurality of said switches in the first said tandem operated switch train extension from the calling line.

27. In a telephone system, a calling line, a

plurality of selective switches, each said switch operated responsive to a plurality of impulses constituting a series applied thereto, the number of said impulses in each series determining the extent of selective operation of the switch operated thereby, an impulse series sending device on the calling line for sending a train of series, means whereby respective series of impulses sent from the calling device will thereupon operate successive said switches to form a tandem operated switch train extension from the calling line, and means operated depending upon what train of series is sent from said sending device for sending an additional series from a point on the extension from the calling line to further link in tandem one of said switches in first said tandem operated switch train extension from the calling line.

28. In a telephone system, a calling line, a called line, a first switch means, a call directing apparatus accessible from said switch means, a non-numerical switch, a numerical switch mechanism, a receiving line accessible from said numerical switch mechanism, means for operating first said switch means to connect the calling line to the call directing apparatus, means operated responsive to effecting last said connection for causing the non-numerical switch to connect the call directing apparatus to the numerical switch mechanism, and means operated responsive to and dependent upon completing said connection to the numerical switch mechanism for causing the call directing apparatus to thereupon initiate its operation to directly operate the numerical switch mechanism to thereby complete connection from the calling line to the called line.

29. In a telephone system, a first called line, switch apparatus for extending connection to said called line, a second called line, automatic switch mechanism, a directing device, and means operated responsive to extending connection to said first called line for causing said directing device to operate to thereby direct said automatic switch mechanism to further extend said connection to said second called line.

30. In a telephone system, a calling line, a first called line, a second called line, automatic switch mechanism for extending connection to a desired one of said called lines responsive to directive control over the calling line, a directing device, and means operated responsive to extending connection to one of said called lines for causing the directing device to operate to thereby direct the operation of said automatic switch mechanism to further extend said connection to the other of said called lines.

31. In a telephone system, a calling line, a called line, a plurality of circuit links connected in tandem effecting a talking connection

from the calling line to the called line, sources of current for energizing the talking conductors of the calling line and a plurality of said circuit links in series, respectively, means controlled over the called line for reversing the current energizing the calling line and at least one of said links while retaining the polarity of the talking conductors of a link of the connection located between the calling line and the link next antecedent to the called line, the same as before the current energizing the calling line was reversed.

32. In a telephone system, a link circuit, automatic switch mechanism for extending connection away from said link, switch means for connecting to said link, an impulse sending device operating from home position for sending a train of impulses to operate said automatic switch mechanism over the link circuit and thereupon return to home position responsive to effecting connection to the link circuit by said switch means, and means for preventing impulses from being sent from the impulse sending device if the connection to the link circuit is broken down and a new connection to the link circuit is substituted, until the impulse sending device has first returned to home position.

33. In a telephone system, a link circuit, automatic switch mechanism, comprising non-numerical switch mechanism and numerical switch mechanism for extending connection away from said link, switch means for connecting to said link, an impulse sending device operated from home position for sending a train of impulses to operate said numerical switch mechanism correspondingly over the link circuit, means for causing the non-numerical switch mechanism to connect the link circuit with the numerical switch mechanism responsive to effecting connection to the link circuit, and means for initiating the operation of the impulse sending device only responsive to the non-numerical switch mechanism effecting connection to the numerical switch mechanism.

34. In a telephone system, a link circuit comprised of not to exceed two conductors, automatic switch mechanism, consisting of non-numerical switch mechanism and numerical switch mechanism for extending connection away from said link, switch means for connecting to said link, an impulse sending device operated from home position for sending a train of impulses to operate said numerical switch mechanism correspondingly over the link circuit, means for causing the non-numerical switch mechanism to connect the link circuit with the numerical switch mechanism responsive to effecting connection to the link circuit, and means for initiating the operation of the impulse sending device only responsive to the non-numerical switch mechanism effecting connection to the numerical switch mechanism.

35. In a telephone system, a link circuit comprised of not to exceed two conductors, automatic switch mechanism, comprising non-numerical switch mechanism and numerical switch mechanism for extending connection away from said link, means for initiating a call on the link circuit, an impulse sending device operated from home position for sending a train of impulses to operate said numerical switch mechanism correspondingly over the link circuit, means for causing the non-numerical switch mechanism to connect the link circuit with the numerical switch mechanism responsive to the initiation of the call, and means for initiating the operation of the impulse sending device only responsive to the non-numerical switch mechanism effecting connection to the numerical switch mechanism.

36. In a telephone system, a link circuit, automatic switch mechanism, comprising non-numerical switch mechanism and numerical switch mechanism for extending connection away from said link, means for initiating a call on the link circuit, an impulse sending device operated from home position for sending a train of impulses to operate said numerical switch mechanism correspondingly over the link circuit, means for causing the non-numerical switch mechanism to connect the link circuit with the numerical switch mechanism responsive to the initiation of the call, and means for initiating the operation of the impulse sending device only responsive to the non-numerical switch mechanism effecting connection to the numerical switch mechanism.

37. In a telephone system, a link circuit, automatic switch mechanism, comprising non-numerical switch mechanism and numerical switch mechanism for extending connection away from said link, means for initiating a call on the link circuit, an impulse sending device operated from home position for sending a train of impulses to operate said numerical switch mechanism correspondingly over the link circuit, means for causing the non-numerical switch mechanism to connect the link circuit with the numerical switch mechanism responsive to the initiation of the call, and means operated over a talking conductor of last said connection for initiating the operation of the impulse sending device only responsive to the non-numerical switch mechanism effecting connection to the numerical switch mechanism.

38. In a telephone system, a circuit link, an impulse contact-set, a sending mechanism, a called line, switch mechanism for extending connection to said link, automatic switch mechanism for extending connection away from said link to the called line, means operated responsive to effecting connection to said link by said switch mechanism for causing said contact-set to be introduced into the

link and to directively operate the automatic switch mechanism under directive control of the sending mechanism by an annexed operation upon the completion of its said directive operation for excluding the contact-set from said link.

39. In a telephone system, a calling line, a circuit link having near and far sections, an open series contact (243) of one of the talking conductors of the near section, a polar relay (233) having its winding in bridge of the talking conductors of the far section, a connector switch having front and back bridge sections for connecting the calling line to the link circuit, a source of current and a relay adapted to be operatively energized over the talking conductors of the respective said bridge sections, a called line, automatic switch mechanism for extending the connection from said link to the called line, an impulse sending contact-set (501), a sending mechanism, means (relay 203) operated responsive to extending the connection to said link for causing the contact-set to be introduced into the far section of the link to directively operate the automatic switch mechanism under directive control of the sending mechanism, means (relay 232) operated by an annexed operation of said sending mechanism upon the completion of its said directive operation for excluding the contact-set from said link and for energizing the polar relay in a first current direction, and means operated responsive to a response on the called line for reversing the direction of current energizing the polar relay to thereby cause said open contact (243) to become closed for the purpose of operatively energizing the back bridge relay to in turn reciprocate the relation of the front bridge section talking conductors with respect to the front bridge relay so that the source of current applied over the front bridge from its corresponding relay will be changed in direction with respect to the calling line subject to control over the called line.

40. In a telephone system, a line having not to exceed two conductors, an automatic switch for terminating the far end of said line, a second line accessible from said switch, an impulse sending device, and means operated over first said line for starting the impulse sending device sending impulses over the first said line, responsive to first said switch seizing said second line.

41. In a telephone system, a line having not to exceed two conductors, an automatic switch for terminating the far end of said line, a second line and terminating automatic switch accessible at its near end from first said switch, an impulse sending device, and means operated over first said line for starting the impulse sending device sending impulses to operate the second said switch over the first said line and over said second line

in tandem, responsive to first said switch seizing said second line.

42. In a telephone system, a line having not to exceed two conductors, an automatic switch for terminating the far end of said line, a second line accessible from first said switch, an impulse sending device, and means operated over a single conductor of first said line for starting the impulse sending device sending impulses over the first said line, responsive to first said switch seizing said second line.

43. In a telephone system, a line having not to exceed two conductors, an automatic switch for terminating the far end of said line, a second line and terminating automatic switch accessible at its near end from first said switch, an impulse sending device, and means operated over a single conductor of first said line for starting the impulse sending device sending impulses to operate the second said switch over the first said line and over said second line in tandem, responsive to first said switch seizing said second line.

44. In a telephone system, a calling line, having not to exceed two conductors, an automatic non-numerical switch for terminating the far end of said line, a numerically positioned called line accessible via said switch, successive linking switches, an impulse sending device, and means operated over first said link for starting the operation of said impulse sending device in sending directive impulses constituting the numerical designation of the called line over first said line to operate certain of said linking switches, responsive to a predetermined operation of first said switch, in order to thereby link a connection from first said line to the called line.

45. In a telephone system, a line having not to exceed two conductors, an automatic switch for terminating the far end of said line, a relay having its winding connected to a conductor of said line at the near end of the line, the winding short-circuited by a contact in said switch, means operated over the line for causing the switch to operate, whereby the short-circuit will be removed by said contact responsive to a predetermined condition of the switch ensuing by reason of its said operation, and a source of current for energizing the relay when the short-circuit is removed.

46. In a telephone system, a line having not to exceed two conductors, a contact at the far end of the line, a relay having its winding connected to a conductor of said line at the near end of the line, the winding short-circuited by said contact, a second line, means operated over first said line for causing first said line to become operatively connected with said second line, means for removing said short-circuit responsive to the said connection being effected, and a source of current

for energizing said relay when the short-circuit is removed.

47. In a telephone system, a line having not to exceed two conductors, a contact at the far end of the line, a relay having its winding connected to a conductor of said line at the near end of the line, the winding short-circuited by said contact, a second line, means operated over first said line for causing first said line to become operatively connected with said second line, means for removing said short-circuit responsive to the said connection being effected, a source of current for energizing said relay when the short-circuit is removed, and an impulse sending device at the near end of first said line which will start sending impulses over said lines in tandem responsive to the relay operating.

48. In a telephone system, a subscriber's line, having not to exceed two conductors, a called line, a trunk line and terminating directly operated switch for linking a connection from the subscriber's line to the called line, an impulse sending device, subscriber operated means controlled over the subscriber's line for causing the subscriber's line to become connected to the trunk line, and switch operated means revertively operated over the subscriber's line responsive to the connection from the subscriber's line to the trunk line becoming effected for starting the operation of the impulse sending device to send impulses over a subscriber's line and the trunk line to operate the said terminating switch by way of effecting a connection from the subscriber's line to the called line.

49. In a telephone system, a trunk link, switch means for extending connection to the trunk link, automatic switch mechanism for extending connection away from the trunk link, an impulse sending device, means for connecting the impulse sending device to a talking conductor of the trunk link and for causing it to send a plurality of impulses to directly operate said automatic switch mechanism to extend connection from the trunk link responsive to extending connection to the trunk link, and automatic means rendered effective by the sending device to disconnect the sending device from the trunk link.

50. In a telephone system, a trunk link, switch means for extending connection to the trunk link, automatic switch mechanism for extending connection away from the trunk link, an impulse sending device, an impulse contact of the impulse sending device, means for introducing the sending contact in a series path with a conductor of the trunk link and for causing it to thereafter momentarily open the series path to thereby operate said automatic switch mechanism responsive to extending connection to the trunk link, and automatic means thereafter rendered effective by the operation of the send-

ing device to exclude the sending contact from the series path.

51. In a telephone system, a trunk link, switch means for extending connection to the trunk link, automatic switch mechanism for extending connection away from the trunk link, an impulse sending device, an impulse contact of the impulse sending device, means for introducing the sending contact in a series path with two talking conductors of the trunk link and for causing it to thereafter momentarily open the series path to thereby operate said automatic switch mechanism responsive to extending connection to the trunk link, and automatic means thereafter rendered effective by the operation of the sending device to exclude the sending contact from the series path.

52. In a telephone system, a link circuit divided into near and far sections, switch means for extending connection to the near section of the link, automatic switch mechanism for extending connection away from the far section of the link, an impulse sending device, means for connecting the impulse sending device to the far section of the link and for causing it to directly operate said switch mechanism to extend connection away from the far section responsive to extending connection to the near section, and automatic means rendered effective by the operation of the sending device to disconnect the impulse sending device and to connect the sections in tandem.

53. In a telephone system, a link circuit divided into near and far sections, the far section having not to exceed two conductors, switch means for extending connection to the near section of the link, automatic switch mechanism for extending connection away from the far section of the link, an impulse sending device, means for connecting the impulse sending device to the far section of the link and for causing it to directly operate said switch mechanism to extend connection away from the far section responsive to extending connection to the near section, and automatic means rendered effective by the operation of the sending device to disconnect the impulse sending device and to connect the sections in tandem.

54. In a telephone system, a link circuit divided into near and far sections, switch means for extending connection to the near section of the link, automatic switch mechanism for extending connection away from the far section of the link, an impulse sending device, means for connecting the impulse sending device to the far section of the link and for causing it to directly operate said switch mechanism to extend connection away from the far section responsive to extending connection to the near section, automatic means rendered effective by the operation of the sending device to disconnect the impulse

sending device and to connect the sections in tandem, and means whereby when the switch means is disconnected from the near section the link circuit will become divided into its 5 sections.

55. In a telephone system, a link circuit divided into near and far sections, switch means for extending connection to the near section of the link, an impulse sending device, means for connecting the impulse sending device to the far section of the link and for causing it to send impulses over the far section responsive to extending connection to the near section, and automatic means rendering effective by the operation of the sending device only after the impulses have been sent to disconnect the impulse sending device and to connect the sections in tandem.

56. In a telephone system, a link circuit divided into near and far sections, switch means for extending connection to the near section of the link, an impulse sending device, means for connecting the impulse sending device to the far section of the link and for causing it to send impulses over the far section responsive to extending connection to the near section, and means for delaying the sending of the impulses dependent upon a specific condition ensuing upon the far section following the connection to the near section, for starting the sending.

57. In a telephone system, a link circuit divided into near and far sections, switch means for extending connection to the near section of the link, an impulse sending device, means for connecting the impulse sending device to the far section of the link and for causing it to send impulses over the far section responsive to extending connection to the near section, and means for delaying the sending of the impulses dependent upon re- 10 vertive control therefor applied over the far section responsive to the connection of the impulse sending device to the far section, for 45 starting the sending.

58. In a telephone system, a link circuit having not to exceed two conductors for a portion of the length of the link, switch means for extending connection to the link, an impulse sending device, means for connecting the impulse sending device to the link to send impulses over said portion of the link responsive to extending connection to the link, and means for delaying the sending of the impulses depending upon re- 15 vertive control therefor applied over said portion of the link, for starting the sending.

59. In a telephone system, a telephone line having not to exceed two conductors for a portion of the length of the line, an impulse sending device, means for connecting the impulse sending device to the line to send impulses over said portion of the line, and means for delaying the sending of the im- 65 pulses depending upon re-vertive control

therefor applied over a single conductor of said portion of the line, for starting the sending.

60. In a telephone system, a telephone line having not to exceed two conductors for a portion of the length of the line, an impulse sending device, means for connecting the impulse sending device to the line to send a train of series of impulses over said portion of the line, and means for delaying the sending of the first impulse of the train depending upon re-vertive control therefor applied over a single conductor of said portion of the line, for starting the sending.

61. In a telephone system, a telephone line having not to exceed two conductors for a portion of the length of the line, an impulse sending device, means for connecting the impulse sending device to the line to send a train of series of impulses over said portion of the line, and means for delaying the sending of the first impulse of the train depending upon re-vertive control therefor applied over said portion of the line, for starting the sending.

In witness whereof, I hereunto subscribe my name this 17th day of August, 1927.

HERBERT M. FRIENDLY.
